UNITED STATES PATENT OFFICE.

ELZEAR MICHAUD, OF INDIANAPOLIS, INDIANA, ASSIGNOR TO ERNEST L. DAYTON.
OF DETROIT, MICHIGAN.

BURNER APPARATUS.

Application filed May 11, 1922. Serial No. 560,110.

My invention relates to burner apparatus, suitable for general heating purposes, but particularly adaptable for use in connection with apparatus for the heating of small buildings, for example, automobile garages, or individual rooms in dwelling houses, office buildings or factories, which comprises a circulatory system for the heating medium, for example, hot water, and heat generating means therefor; and the principal objects of the present invention are to provide improved burner apparatus of simple and compact construction, and which will be safe, efficient and require but little attention in its 15 operation.

Another object is to provide improved means for heating the circulating medium so arranged that substantially all the heat generated will be conserved and efficiently 20 used for its intended purpose.

Further objects of my present invention are to provide improved means for supplying the fuel to the burner and novel means for igniting the fuel in starting.

In its preferred form the invention contemplates providing means whereby the fuel will be gasified before reaching the burner, and a further object of the invention is to provide means whereby a portion of the gas 30 generated will be accumulated in the fuel supply tank so that the body of liquid fuel therein will be under a constant pressure.

The invention consists in the novel constructions, arrangements and devices to be 35 hereinafter described and claimed, for carrying out the above stated objects and such other objects as will appear from the following specification.

The invention is illustrated in a certain 40 preferred embodiment in the accompanying drawings wherein

Fig. 1 is a longitudinal sectional view of an apparatus embodying the principles of my invention;

Figs. 2, 3, and 4 are sectional views taken 45 respectively, on the lines 2-2, 3-3, and 4-4 of Fig. 1; and

Fig. 5 is a diagrammatic view of the heat generating means and the preferred fuel 50 supply and ignition systems therefor.

Like characters of reference designate like parts in the several figures.

The invention has been illustrated in connection with a portable radiator. The radiator section 14^a is formed so as to provide a 55

tank 29 for the storage of liquid fuel and a compartment 30 for the vibrator 31 and battery 32 of the ignition system, this compartment being located in one corner and provided with a door 33. The tank 29 is 60 provided with an opening 34 for filling purposes which is normally closed by a screw plug 35. The liquid fuel feeds by gravity from the tank 29 through a pipe 36 to a coil 37 and thence to a fitting 38 which is provided 65 with a valved orifice. The coil and valved orifice constitute the burner and are located under the water chamber 25 of the radiator and are enclosed within a suitable casing 39. A pipe 40 leads from the fitting 38 back to 70 the top of the fuel supply tank, the purpose of which will be hereinafter described.

An ignition system is preferably used for starting purposes. A spark plug 41 is secured to the casing 39 the terminal 42 thereof 75 of projecting into and being substantially concentric with the coil 37. A tubular screen 43 of wire gauze is fitted within the coil 37 and forms the other terminal of the spark plug. On a bracket 44 secured to the 80 casing 39 is mounted an insulated contact 45. The valve in the fitting 38 is of the ordinary needle type and is arranged so that the jet of fuel passing therefrom will impinge 85 against the coil 37. The stem 46 of the valve is provided with a member 47 which is secured thereto so as to make contact with the member 45 when the valve stem is turned. The high tension terminal 48 of the vibrator is connected to the spark plug 90 by a conductor 49. The contact member 45 is connected to the battery 32 by a conductor 50. The other side of the battery is connected to terminal 51 of the vibrator by a conductor 52. Terminal 53 is connected 95 to ground 54 by a conductor 55.

For the sake of clearness the contact member 47 is shown as being grounded at 56 and the screen 43 as being grounded at 57. The screen 43 and member 47 being a part of the 100 apparatus are electrically connected and in practice it would only be necessary to ground the conductor 55 to the apparatus.

The space 58 within the casing 39 constitutes a combustion chamber. The casing is 105 formed with an opening 59 to permit the entrance of air. The warm air from the combustion chamber passes upwardly through the annular space 60 surrounding the water chamber 25 into the pipe 61, passing out 110

through the openings 62 provided in the hood 63 attached to the top of pipe 61. The currents of air passing upwardly in the pipe 61 serve to heat a pipe 27 extending through the pipe 61 from the water chamber 25 to the upper end portion of the radiator. The pipe 61 acts as a flue and aids in drawing fresh air into the combustion chamber 58. The opening 59 and the pipe 61 are of such relative proportions as to permit sufficient fresh air to be drawn into the combustion chamber 58 and substantially complete combustion of the fuel is obtained.

15 *Operation.*

The ignition system is controlled by the contact member 47 on the valve stem 46 which member is arranged so as to permit the valve to be opened slightly before the member makes contact with the member 45, this arrangement permitting a small quantity of the liquid fuel to be sprayed onto the screen 43 for starting purposes. When the member 47 is in contact with the member 45 current flows from the battery 32 through conductor 52, terminal 51, through the low tension coil of the vibrator (not shown), terminal 53, conductor 55, ground 54, ground 56, contact member 47, contact member 45, and conductor 50 to battery 32. Current flowing through the circuit described produces a current in the secondary coil (not shown) of the vibrator, the intensity of which is sufficient to cause a spark to jump from terminal 42 to screen 43 which ignites the fuel on the screen, the high tension current taking the following path: Terminal 48 through conductor 49 to spark plug 41, terminal 42, where it jumps across the spark gap to screen 43 grounded at 57 thence to ground 54, conductor 55, terminal 53 of the vibrator which acts also as a terminal for the high tension or secondary coil, as is common in vibrators. After the fuel has been ignited the valve stem 46 is turned so that the member 47 is out of contact with the member 45, which automatically cuts out the ignition system.

50 The coil 37 causes the flame to spread out so that substantially the entire bottom surface of the chamber 25 is subjected to the action of the flame. The water in the chamber 25 is heated to a high temperature which causes it to circulate upwardly through the pipe 27 and into the radiator. The chamber 25 and pipe 27 constitute a boiler for heating the circulating medium.

Gasoline is preferably used for fuel. The fuel feeds by gravity from the tank to the coil 37 where it is completely gasified, assuming normal operating conditions before passing to the orifice in the fitting 38. Not all the gas generated passes through the orifice in the fitting 38. A portion of it returns 65 through the pipe 40 to the supply tank.

The gas accumulates in the tank and the liquid fuel therein is under a pressure. The amount of pressure which accumulates in the tank depends upon the size of the orifice in the fitting 38. I have found that the best 70 results are obtained when the orifice is of sufficient size to permit a pressure of approximately 15 pounds to build up in the supply tank; and by proper setting of the stem 46 the pressure in the tank can be maintained substantially constant. The pressures in the pipes 36 and 40 are balanced against each other at all times. If the pressure in the pipe 40 tends to rise above normal 75 its influence is exerted against the head 80 of liquid fuel in the pipe 36 and the flow of liquid fuel therein is retarded until normal conditions obtain in the pipe 40. If, however, the pressure in the pipe 40 should tend to drop below normal the flow of fuel 85 through the pipe 36 will be accelerated which will result in more gas being produced than will be consumed and the pressure in the pipe 40 will immediately build up to normal.

The gasification of the liquid fuel trapped 90 in the coil 37, under normal operating conditions, is complete and instantaneous. An expansion takes place in the coil which results in pulsations or bubbles working backwardly through the pipe 36 and upwardly 95 through the body of liquid fuel contained in the tank. This bubbling action is uniform and results in a certain portion of the fuel being brought into intimate relationship with the heavier gases accumulated in the 100 tank, these gases tending to filter through the body of the liquid fuel. The temperature of the fuel is cold enough to condense the heavier gases but warm enough to absorb the condensable elements. The heavier 105 hydrocarbons settle to the bottom of the tank and pass on to the burner. Thus the operation of the fuel system in this manner results in a continuous refining process of the fuel stored in the tank. I have found that 110 the gas which accumulates in the tank, after the system has been in operation for a few hours, in the manner described is a substantially fixed and noncondensable gas.

Under normal operating conditions the 115 temperature of the gas returning to the supply tank through the pipe 40 will be quite high. In fact, approximately as much heat will be given off by the surface of the radiator section 14^a as by any one of the other 120 sections. If, for any reason the flame should be extinguished and the valve in the fitting 38 not closed the accumulated gas will pass out through the valve so long as the pressure is above atmospheric. Some gas, 125 however, will be trapped in the tank and as it cools and contracts quite rapidly a vacuum will be established therein. A certain quantity of gas will be trapped in the coil 37. Under these conditions I have found 130

that the vacuum established in the tank will be sufficient to hold the liquid fuel in the tank in suspension and prevent it from flowing out through the orifice in the fitting 38.

5 The apparatus is safe to operate and very efficient. Substantially all the heat generated is conserved and used for its intended purpose. The apparatus is self contained and the usual radiation losses, which are inevitable when the radiators are located at a distance from the boiler, are entirely avoided. The apparatus requires but little attention to operate and for this reason it is particularly adaptable for the heating of 10 small buildings, like an automobile garage, or individual rooms of a house, factory or other buildings. The apparatus being mounted on a single base may easily be moved from place to place if desired.

20 The expansion which takes place in the coil 37 and the conditions obtaining in the pipes 36 and 40 effectively prevent the accumulation of any deposit of hydrocarbon therein.

25 I do not intend to limit my invention to the details of construction shown and described except only in so far as certain of the appended claims are specifically so limited, as it will be obvious to those skilled in 30 the art that various modifications may be made without departing from the spirit of my invention.

I claim:

1. In an apparatus of the class described, 35 the combination of a liquid fuel supply tank, a pipe line leading from the tank and returning thereto and comprising means for trapping liquid fuel to which the fuel feeds by gravity from the tank through the pipe 40 line, and a burner device connected by the pipe line with the tank, the supply pipe between the tank and the burner device lying entirely below the normal level of the fuel in the tank, said burner device having an 45 orifice through which a jet of liquid fuel passes from the pipe line by gravity feed from the tank into contact with said trapping means and through which gas is forced 50 for feeding a flame against said trapping means when the trapping means has become heated.

2. In an apparatus of the class described, 55 the combination of a liquid fuel supply tank, a pipe line leading from the tank and returning thereto and comprising a coil for trapping liquid fuel to which the fuel feeds by gravity from the tank through the pipe 60 line, and a burner device connected by the pipe line with the tank, the supply pipe between the tank and the burner device lying entirely below the normal level of the fuel

in the tank, said burner device having an orifice through which liquid fuel flows from the pipe line by gravity from the tank into contact with said coil and through which gas 65 is forced for feeding a flame against such coil when the coil has become heated.

3. In an apparatus of the class described, 70 the combination of a liquid fuel supply tank, a pipe line leading from the tank and returning thereto and comprising a coil having a plurality of convolutions in superposed relation serving as a trap with respect to the sudden expansion therein of liquid fuel to which coil the fuel feeds by gravity 75 from the tank through the pipe line, and a burner device connected by the pipe line with the tank, the supply pipe between the tank and the burner device lying entirely below the normal level of the fuel in the 80 tank, said burner device having an orifice through which liquid fuel flows from the pipe line by gravity from the tank into contact with said coil and through which gas 85 is forced for feeding a flame against such coil when the coil has become heated.

4. In an apparatus of the class described, 90 the combination of a liquid fuel supply tank, a pipe line leading from the tank and comprising means for trapping liquid fuel to which the fuel feeds by gravity from the tank through the pipe line, a burner device connected by the pipe line with the tank, the supply pipe between the tank and the burner device lying entirely below the normal level of the fuel in the tank, said burner 95 device having an orifice through which a jet of liquid fuel passes from the pipe line by gravity feed from the tank into contact with said trapping means and through which gas 100 formed in the trapping means when the trapping means has become heated is forced for feeding a flame against said trapping means, valve means for closing said orifice, and other pipe line means leading from said 105 burner device to said tank for returning to the tank the surplus gas not consumed at the burner.

5. In apparatus of the class described, the combination with a burner having a valved orifice, means to supply fuel to said burner, and a gauze screen associated with said burner against which the fuel impinges, of ignition means including a spark plug associated with said burner and a circuit closing device mounted on the handle of said valve, said screen forming one terminal of the spark gap whereby upon the opening of said valve a spark jumps from said plug to said screen and ignites the fuel thereon.

ELZEAR MICHAUD.
